MEANS FOR REMOVING HEAT INDICATOR
BULBS

Basil Paul Strong, Atwater, Ohio

Application June 17, 1938, Serial No. 214,345

4 Claims. (Cl. 29—86.1)

My invention relates to means for and a method of removing heat indicator bulbs from the motor head casting of automobiles or the like. The heat indicator bulbs used on automobile engines are immersed in a body of water or other motor cooling liquid and the impurities in the cooling liquid build up a residue which corrodes the bulb and the motor head casting at their line of contact, causing the bulb to adhere or "freeze" to the casting, thus resisting the ready removal of the bulb from the casting. Heretofore one method used to remove the bulb has been to insert a tool through an adjacent opening in the motor head casting and with it press against the 10 end of the bulb, but owing to the angular position of the centerline of the bulb with respect to the centerline of the opening, in some cases 45 degrees, such pressure when applied sets up a bending moment in the bulb, which, having a thin 15 fragile shell of soft metal, is dented or bent and distorted in such a manner as to render the bulb ineffective for further use. Another common method of attempting to loosen and remove the bulb from its seat in the casting, is to pull on the 20 indicator tube attached to the bulb, which results in either breaking the tube or in so distorting it as to render the reading on the automobile dash 25 indicator out of calibration.

The object of my invention is to eliminate 30 these troubles and to provide a method of and means for forcing the heat indicator bulb out of its bearing in the motor head casting by means of pressure exerted in a direct line with the longitudinal axis of the bulb thus avoiding the 35 setting up of any bending action in the bulb and any distortion of the latter.

A further object is to provide a simple tool 40 wherein the shape of that portion of the tool which contacts or bears against the inner end of the bulb, will conform accurately with the shape 45 of the end of the bulb so as to distribute pressure applied to such end uniformly over the area of contact to prevent any deformation of the shape of the bulb; as it has been found that even a slight dent in the shell of the bulb will 50 render the entire heat indicating system ineffective.

A further object is to provide a method whereby the heat indicating bulb may be removed 55 after my tool is applied, by simply turning out the retaining nut which is used normally to keep the bulb held tightly against its seat in the motor head casting.

With the foregoing objects outlined and with other objects in view which will appear as the

description proceeds, the invention consists in the novel features hereinafter described in detail, illustrated in the accompanying drawing and more particularly pointed out in the appended claims.

In the drawing:

Fig. 1 is a section of the motor head casting with my device shown in place.

Fig. 2 is a side elevation of the frame of my device.

Fig. 3 is an enlarged section at 3—3 of the lower end of the frame.

Fig. 4 is a plan view of the upper end of the lever.

Fig. 5 is an elevation of the lower end of the lever showing semi-spherical recesses to fit the inner end of heat indicator bulbs of different sizes.

In the particular embodiment of my invention shown in the above drawing, 1 designates a portion of an automobile motor head casting, having a nipple 2 about which fits a hose 3 leading from the motor head to radiator not shown. Hollow portion 4 of the motor head casting forms a chamber for the motor cooling liquid. 5 is a heat indicator bulb consisting of a thin closed shell having a semi-spherical inner end 6 and an outer end 7 through which indicator tube 8 extends from bulb 5 up to an indicator dial (not shown) usually located on the instrument panel on the dash of an automobile.

The bulb is inserted into the cooling chamber of the head casting where it is immersed in the cooling liquid and is held in place by threaded retaining nut 10 which presses the shoulder 11 on outer end of bulb against a seat in the motor head casting, thus sealing it against any leakage of cooling fluid from the chamber of the head casting.

12 designates the main frame or stationary jaw of my device which is provided at its lower end with a yoked portion (Figs. 2 and 3) adapted to readily fit down over the tube 8 and to contact the outer surface of retaining nut 10. On the forked portion of the frame 12 I provide an arch-shaped projection 13 which is adapted to fit into the hole in nut 10 between the nut and the tube so as to hold the frame in place and prevent it from turning when the pressure is applied in turning nut 10 out of its position. Through a hole in the upper end of frame 12, I insert pin 14 upon which movable lever or jaw 15 is pivoted for free oscillation. At the upper end of frame 12, I also provide an integrally formed boss 16 which has a threaded hole 55

adapted to receive the screw threads on adjusting nut 17 which is adapted to bear against a flat surface 18 on the upper portion of lever 15.

Lever arm 15 is provided near its lower end 5 with one or more cupped or semi-spherical recesses 19, 19' adapted by their shape to fit snugly against the semi-spherical end 6 of bulb 5. The reason I sometimes desire to provide more than one semi-spherical recess in the lever 10 15 is to provide for several different lengths of bulbs and different angles between center-line of bulb and the vertical center-line of the nipple 2.

In using my method and device for removing a bulb from the motor, the retaining nut 10 is 15 loosened slightly with an ordinary hand wrench, then my device is placed in the position shown in Fig. 1; the adjusting screw 17 is tightened down lightly with the fingers, then nut 10 is unscrewed thus exerting outward pressure against the lower 20 end of frame 12. This pressure is transferred through frame 12 and lever 15 to the rear end of bulb in a direction coincident with its longitudinal axis, thus forcing the bulb loose and out of the motor head casting without setting up a 25 bending moment in the bulb or otherwise denting or injuring it.

From the foregoing, it is believed that the construction, operation and advantages of my improved tool will be readily understood by those 30 skilled in the art, and I am aware that changes may be made in the details disclosed without departing from the spirit of the invention as expressed in the claims.

What I claim and desire to secure by Letters

35 Patent is:

1. A tool of the character described for removing heat indicator bulbs of the type arranged in an opening in a water jacket or the like and held by a screw device, the jacket also having a 40 second opening for the circulation of water to and from said jacket, said tool comprising connected first and second arms, the first arm being adapted to extend into the second opening in the jacket and being provided with a recess adapted 45 to receive the rounded inner end of the heat indicator bulb, the second arm being adapted to be disposed outside the jacket and having a bifurcated end adapted to straddle a tube leading from the outer end of the bulb and being arranged at an angle to said first arm and in line of movement of the screw device, which, when unscrewed will apply pressure against the second arm, said bifurcated end of the second arm and the recess in said first arm being in alignment, whereby the pressure applied against the 50 second arm will be transferred through said first arm against the inner end of the bulb in a direction coincident with the longitudinal axis of the bulb.
2. A tool of the character described for removing heat indicator bulbs of the type arranged in an opening in a water jacket or the like and held by a screw device, the jacket also having a second opening for the circulation of water to and from 55 said jacket, said tool comprising pivotally connected arms, one arm being adapted to extend into the second opening in the jacket and being provided between its end and the point of pivot-

ing with a recess adapted to receive the inner end of the heat indicator bulb, the other arm being adapted to be disposed outside the jacket and being bifurcated at a point remote from the point of pivoting, said bifurcated end being adapted to straddle a tube leading from the outer end of the indicator bulb and being in line of movement of the screw device, which, when unscrewed will apply pressure against the second arm in a direction away from the first arm, and means arranged at the point of pivoting of said arms for transmitting said pressure from the second arm to the first arm for moving the recessed portion of the first arm toward the bifurcated portion of the second arm.

3. A tool of the character described for removing heat indicator bulbs of the type arranged in an opening in a water jacket or the like and held by a screw device, the jacket also having a second opening for the circulation of water to and from said jacket, said tool comprising pivotally connected arms, one arm being adapted to extend into the second opening in the jacket and being provided between its end and the point of pivoting with a recess adapted to receive the inner end of a heat indicator bulb, the other arm being adapted to be disposed outside the jacket and being bifurcated at a point remote from the point of pivoting, said bifurcated end being adapted to straddle a tube leading from the other 30 end of the bulb and being in line of movement of the screw device, which, when unscrewed will apply pressure against the second arm in a direction away from the first arm, and adjustable means carried by one arm and bearing against the other arm for transmitting said pressure from the second arm to the first arm for moving the recessed portion of the first arm toward the bifurcated portion of the second arm.

4. A tool of the character described for removing heat indicator bulbs of the type arranged in an opening in a water jacket or the like and held by a retaining nut, the jacket also having a second opening for the circulation of water to and from said jacket, said tool comprising pivotally connected arms, one arm being adapted to extend into the second opening in the jacket and being provided between its end and the point of pivoting with a recess adapted to receive the inner end of the heat indicator bulb, the other arm being adapted to be disposed outside the jacket and being bifurcated at a point remote from the point of pivoting, said bifurcated portion of the second arm being adapted to straddle a tube leading from the other end of the bulb and to contact the outer surface of the bulb retaining nut, which, when unscrewed will apply pressure against the second arm in a direction away from the first arm, said second arm having a projection thereon, adjacent its bifurcated portion, adapted to fit between the inner surface of a hole in the retaining nut and the tube, and means arranged at the point of pivoting of said arms for transmitting said pressure from the second arm to the first arm for moving the recessed portion of the first arm toward the bifurcated portion of the second arm.

BASIL PAUL STRONG.
